Primary Examiner — Cynthia Ramirez*(74) Attorney, Agent, or Firm* — Patterson Intellectual Property Law, P.C.; Edward D. Lanquist, Jr.; Alex H. Huffstutter(57) **CLAIM**

The ornamental design for a small craft anchor winch, as shown and described.

DESCRIPTION

FIG. 1 is a front perspective view showing the small craft anchor winch showing my new design.

FIG. 2 is a rear perspective view of the small craft anchor winch of FIG. 1.

FIG. 3 is a rear elevation view of the small craft anchor winch of FIG. 1.

FIG. 4 is a front elevation view of the small craft anchor winch of FIG. 1.

FIG. 5 is a right side elevation view of the small craft anchor winch of FIG. 1.

FIG. 6 is a left side elevation view of the small craft anchor winch of FIG. 1; and,

FIG. 7 is a top plan view of the small craft anchor winch of FIG. 1.

The broken lines shown in the figures are for the purpose of illustrating environmental structure and form no part of the claimed design.
